UNITED STATES PATENT OFFICE.

ROBERT MIEHLE, OF CHICAGO, ILLINOIS.

MECHANISM FOR ADJUSTING PAPER UPON FEED-BOARDS.

1,272,075.

Specification of Letters Patent.

Patented July 9, 1918.

Application filed November 27, 1916. Serial No. 133,763.

To all whom it may concern:

Be it known that I, ROBERT MIEHLE, citizen of the United States, residing at Chicago, in the county of Cook and State of Illinois, have invented a certain new and useful Improvement in Mechanism for Adjusting Paper Upon Feed-Boards, of which the following is a full, clear, concise, and exact description.

10 My invention relates to boards from which paper is to be manually fed to folding machines, printing presses, etc., and has for its object the provision of means for changing the positions of sheets or lifts of paper with 15 reference to such boards. In practising my invention I employ roller mechanism to the rear of such boards to impart or permit movement of sheets or lifts of paper longitudinally of the boards, this roller mechanism desirably including a plurality of rollers having 20 parallel axes of rotation that are at right angles to the general line of travel in which the paper is being fed. The boards are desirably rearwardly continued into the region 25 of the rollers and when they are thus continued the rollers preferably permanently project above such rearward continuations to have tractive engagement with the paper upon the same. When the boards have 30 rear paper or lift receiving divisions there are afforded composite stationary and movable paper supporting structures to the rear of the feed boards proper.

I will explain my invention more fully by 35 reference to the accompanying drawing showing the preferred embodiment thereof and in which Figure 1 is a plan view of a feed board equipped with my invention and shown in association with an impression 40 cylinder of a printing press, parts being broken away; Fig. 2 is a view on line 2—2 of Fig. 1; Fig. 3 is a detail view of some of the parts taken on the line 3—3 of Fig. 1; and Fig. 4 shows a detail of construction 45 taken on the line 4—4 of Fig. 1.

Like parts are indicated by similar characters of reference throughout the different figures.

The drawing shows the association of a 50 feed board equipped with my invention with a printing press (of which a printing cylinder 1 is shown in Figs. 1 and 2) but the invention is not to be limited to such association.

The front division 2 of the feed board is 55 the feeding end thereof from which the sheets of paper are delivered singly to be operated upon by the mechanism to which they are to be fed such as a printing press. The rear division 2¹ of the board supports 60 the lift of paper indicated at 3 in Fig. 2, the sheets being led from the lift or pile of paper 3 to the feeding portion 2 of the board which is customarily hinged at 4. The lift supporting portion of the feed board is mainly 65 the rear division 2¹, a portion of the lift being usually carried upon the rear portion of the feed board division 2. The rear division of the feed board is equipped with rollers 5 having spherical enlargements or sections 6 that project through circular openings in the feed board slightly above its paper supporting surface or the plane of its paper supporting surface to have tractive 70 engagement with the paper that is upon the 75 same. The mountings for the rollers are so disposed as to have the axis of rotation of the rollers sufficiently below the paper supporting surface or the plane of the paper supporting surface to permit the rollers to 80 project only slightly above such surface or plane, and the rollers are disposed transversely of the board so that they may rotate longitudinally of the board or in the line of feeding. The rear portion of the forward 85 division 2 of the feed board is equipped with rollers 7 having spherical enlargements or sections 7¹ that similarly project through circular openings in this feed board division to have tractive engagement with the 90 paper that is upon the same. These rollers are preferably limited to movement longitudinally of the feed board and the paper is prevented from working in between the 95 rollers and the feed board owing to the presence of portions of the feed board between the roller sections 6 and the roller sections 7¹. In the preferred form of the invention the portions of the feed board between these roller sections continue from 100 side to side of the rollers, the feed board divisions being thus unbroken or continuous in the region of the rollers except for the mere presence of the disconnected openings through which the spherical sections of the 105 rollers project. All of the rollers 5 upon the rear division of the board are preferably equipped with roller driving mechanism.

which also desirably operates the forward one of the two rollers upon the forward division of the board, the rear roller upon the forward division of the feed board being desirably an idler. The driving mechanism illustrated comprises sprocket pinions 10 located upon one side of the feed board and fixed upon the adjacent ends of the shafts 11 that carry the rollers 5. An endless sprocket chain 12 passes over the tops of these pinions and is maintained in engagement with the teeth of these pinions by means of the guard plate 13. The end of one of the shafts 11 that carries a sprocket pinion 10 is desirably equipped with a hand crank 17 or any other means for furnishing power, the shaft 11 selected for the attachment of the crank 17 thereto being desirably that upon which the rearmost roller 5 is mounted. The next to the foremost roller 5 also has a crank 18 or some other suitable means for furnishing power connected therewith, the crank 18 being located on the side of the feed board which is opposite to that upon which the crank 17 is located. By means of either crank 17 or 18 the sprocket pinion 10, rigid with respect thereto, may be turned to cause the travel of the endless sprocket chain and the simultaneous and synchronous rotation 30 of the rollers 5 and the forward roller 7. The crank 17 is particularly serviceable for operation by the attendant when he is at the left of the board and is loading a lift thereupon.

35 To prevent any of the rollers 5 and the forward roller 7 from being turned by the shaking of the machine or the action of the lift thereupon and thereby cause undesirable movement of the paper upon the same, I employ a suitable braking device, one form 40 of braking device being illustrated in Figs. 1 and 4 where I have shown a braking clamp 19 embracing the shaft 11 of the next to the foremost roller 5 and comprising two 45 jaws hinged together at one end of the clamp and coupled at the other end of the clamp by an adjusting wing screw 20. The braking clamp is so adjusted that the shafts 11 may be turned notwithstanding the braking 50 action of the clamp but which braking action is sufficient to prevent the rollers from turning due to the shaking of the machine and the action of the lift of paper upon the rollers 5 and the foremost roller 7.

55 In the use of my device all of the sheets in the lift may be easily adjusted to the position of feeding, this being true even of the last remaining bottom sheet, and I do not therefore wish to limit myself to the adjustment 60 of the entire lift of paper by means of my invention.

While I have herein shown and particularly described the preferred embodiment of my invention I do not wish to be limited to the precise details of construction shown as

changes may readily be made without departing from the spirit of my invention, but having thus described my invention I claim as new and desire to secure by Letters Patent the following:—

70

1. The combination with a feed board from which paper is to be manually fed; of rollers rotatable in the line of feeding and projecting through the feed board to engage the paper thereupon; and mechanism for effecting the rotation of the rollers.

75

2. The combination with a feed board from which paper is to be manually fed; of rollers rotatable in the line of feeding and projecting through the feed board to engage the paper thereupon; and manually operated mechanism for effecting rotation of the rollers.

80

3. The combination with a feed board from which paper is to be manually fed; of rollers rotatable in the line of feeding and projecting through the feed board to engage the paper thereupon; manually operated mechanism for effecting rotation of the rollers; and braking mechanism for preventing 90 abnormal rotation of the rollers.

95

4. The combination with a feed board from which paper is to be manually fed; of rollers rotatable in the line of feeding and projecting through the feed board to engage the paper thereupon; mechanism for effecting rotation of the rollers; and braking mechanism for preventing abnormal rotation of the rollers.

100

5. The combination with a board from which paper is to be manually fed; of paper supporting rollers located to the rear of the board and having tractive engagement with paper upon the same, said rollers being rotatable in the line of feeding; and manually operated mechanism for effecting the rotation 105 of the rollers.

105

6. The combination with a board from which paper is to be manually fed; of paper supporting rollers located to the rear of the board and having tractive engagement with paper upon the same, said rollers being rotatable in the line of feeding; manually operated mechanism for effecting the rotation 110 of the rollers; and braking mechanism for preventing abnormal rotation of the rollers.

115

7. The combination with a board from which paper is to be manually fed; of paper supporting rollers located to the rear of the board and having tractive engagement with paper upon the same, said rollers being rotatable in the line of feeding; mechanism for effecting the rotation of the rollers; and braking mechanism for preventing abnormal rotation of the rollers.

120

8. The combination with a feed board for supporting paper thereupon that is to be fed therefrom, said feed board having openings therethrough; of rollers formed in spaced apart sections that project through said

130

openings to have tractive engagement with the paper upon the feed board; and mechanism for effecting the rotation of the rollers.

9. The combination with a feed board for supporting paper thereupon that is to be fed therefrom, said feed board having circular openings therethrough; of rollers formed in spaced apart spherical sections that project through said openings to have tractive engagement with the paper upon the feed board; and mechanism for effecting the rotation of the rollers.

10. The combination with a feed board for supporting paper thereupon that is to be fed therefrom, said feed board having openings therethrough; of rollers formed in spaced apart sections that project through said openings to have tractive engagement with the paper upon the feed board; and mechanism for effecting the rotation of the rollers, the feed board being extended into the spaces between the roller sections.

11. The combination with a feed board for supporting paper thereupon that is to be fed therefrom, said feed board having circular openings therethrough; of rollers formed in spaced apart spherical sections that project through said openings to have tractive engagement with the paper upon the feed board; and mechanism for effecting the rotation of the rollers, the feed board being extended into the spaces between the roller sections.

12. The combination with a feed board for supporting paper thereupon that is to be fed therefrom, said feed board having openings therethrough; of rollers formed in

spaced apart sections that project through said openings to have tractive engagement with the paper upon the feed board; and mechanism for effecting the rotation of the rollers, the feed board being continued from side to side of the rollers through the spaces between the roller sections.

13. The combination with a feed board for supporting paper thereupon that is to be fed therefrom, said feed board having circular openings therethrough; of rollers formed in spaced apart spherical sections that project through said openings to have tractive engagement with the paper upon the feed board; and mechanism for effecting the rotation of the rollers, the feed board being continued from side to side of the rollers through the spaces between the roller sections.

14. The combination with a board from which paper is to be fed; of paper supporting rollers located to the rear of the board and having tractive engagement with paper upon the same, said rollers being rotatable in the line of feeding; sprocket pinions upon ends of the rollers; an endless sprocket chain engaging the outermost pinions and having the stretch thereof intervening between these outermost pinions engaging the intervening pinions; and a guard for holding this stretch of the chain in engagement with such intervening pinions.

In witness whereof, I hereunto subscribe my name this twenty-fourth day of November A. D., 1916.

ROBERT MIEHLE.
